[57] CLAIM

The ornamental design for a pet shelter, as shown and described.

DESCRIPTION

FIG. 1 is a perspective view taken from the top, front and right side of a pet shelter showing my new design;
FIG. 2 is a front elevational view thereof;
FIG. 3 is a rear elevational view thereof;
FIG. 4 is a side elevational view thereof, the opposite side being identical to the side shown;
FIG. 5 is a top plan view thereof; and
FIG. 6 is a bottom plan view thereof.
